Primary Examiner — Darlington Ly

(57) **CLAIM**

The ornamental design for a velomobile, as shown and described.

DESCRIPTION

1. Velomobile

1.1 is a left side elevation view of a velomobile embodying our new design;

1.2 is a front elevation view thereof;

1.3 is a rear elevation view thereof;

1.4 is a top plan view thereof;

1.5 is a left side elevation view thereof, wherein the rear body is elevated;

1.6 is a left side elevation view thereof, wherein the canopy is opened; and

1.7 is a left side elevation view thereof, wherein the rear body is elevated and canopy is opened.

1 Claim, 7 Drawing Sheets
